Patented Nov. 11, 1919.

Fig. 1.

Fig. 2.

Fig. 6.

Fig. 3.

A detailed line drawing of a glass tube. The tube is shown in perspective, pointing towards the viewer. It has a wider upper section and a narrower lower section. A small, horizontal, rectangular cutout or constriction is located on the upper section, near the top. This cutout is labeled with a lowercase 'd' in a cursive script. The drawing uses fine lines and cross-hatching to represent the texture of the glass.

UNITED STATES PATENT OFFICE.

PHILIP ALÒ, OF NEW YORK, N. Y., ASSIGNOR OF ONE-HALF TO ALBERT B. PEIRCE, OF NEW YORK, N. Y.

NON-REFILLABLE BOTTLE.

1,321,411.

Specification of Letters Patent. Patented Nov. 11, 1919.

Application filed January 2, 1918. Serial No. 209,830.

To all whom it may concern:

Be it known that I, PHILIP ALÒ, a citizen of the United States, residing in the city of New York, borough of Manhattan, county 5 and State of New York, have invented a certain new and useful Non-Refillable Bottle, of which the following is a specification.

This invention is a non-refillable bottle, and the object of the invention is a bottle 10 of the character specified which is simple and economical to make and efficient in operation.

Speaking generally, the invention, from a structural standpoint, embodies a weighted valve, preferably of an inverted conical shape and provided at its upper portion with spacing legs, a coöperating valve seat in the neck of the bottle, and a bottle cap for the valve seat and valve, said cap being 20 provided with an outlet and having spacing legs depending from its top and at the lower ends of which spacing legs is a liquid baffle or barrier.

In the accompanying drawings I have 25 illustrated several practical embodiments of the invention, but these constructions are to be regarded as the preferred embodiments of the invention though not necessarily the exclusive ones. Referring to the drawings, 30 Figure 1 is a sectional elevation of the neck of a bottle showing the invention applied thereto;

Fig. 2 is a similar view showing the parts in tilted position;

35 Fig. 3 is a sectional elevation on line 3—3 Fig. 1;

Fig. 4 is a perspective view of the valve and its spacing legs;

Fig. 5 is a slightly modified form of the 40 invention shown in Fig. 1, the valve seat and valve cap being integral, and

Fig. 6 is a further modified form wherein the valve seat is integral with the neck or mouth of the bottle.

45 Referring to the drawings, and particularly to Figs. 1, 2, 3, and 4, A designates the neck of a bottle, B a valve seat, D a weighted valve provided with spacing legs d, and E represents a bottle cap having an outlet 50 e and provided with depending spacing legs e' at the ends of which is a baffle plate e''. It will be noted that the exterior surface of the mouth of the bottle is provided with

a groove into which the lower thin edge or portion of the valve seat may be curled and 55 thus secured.

Referring to Fig. 5, A' designates the neck of the bottle, B' the valve seat, D' the valve with its spacing legs d', E' the bottle cap formed integral with valve seat B', said 60 cap having an outlet f, and the depending spacing legs f' at the ends of which is a baffle plate f'', all of which members correspond to those previously described in connection with Figs. 1 and 2. In making this type of 65 constructure it is necessary to provide for the assembling therein of valve D'. This may be accomplished by making the valve seat B' and cap E' in two parts, i. e., divided vertically. The valve may then be positioned between the parts, whereupon they may be united in any suitable way, depending 70 upon the character of the material of which the parts are constructed.

Referring to Fig. 6, A² designates the 75 neck of the bottle, provided with a valve seat B² formed integral therewith, D² the valve provided with the spacing legs d², E² the bottle cap having an outlet g and the depending spacing legs g' to the ends of which 80 is secured the baffle plate g².

It will be noted that the valve is made hollow, thereby providing for the inflow of liquid thereto in the event it is attempted to refill the bottle, the thus introduced liquid 85 serving to assist gravity in impelling the valve to a closed position on its seat. Under certain conditions, however, it is desirable to make the valve solid, thus relying entirely 90 on the weight of the valve to effect the closing thereof.

From the foregoing description, the operation of the invention will be readily understood, but it may be briefly described as follows: The bottle having been filled as usual, and the valve D, valve seat B and cap E having been assembled in the neck of the bottle, the valve automatically positions itself tightly on the valve seat by gravity, but when the bottle is tilted, the valve drops free from the valve seat, the limit of its movement being determined by the length of the spacing legs d, the liquid is free to flow from the bottle around the baffle plate e'' and through the outlet e. If, however, it is attempted to introduce liquid into the bottle, 100 105

the valve assumes its closed position on the valve seat, and, more especially if it is attempted to introduce liquids under pressure into the bottle such as ordinary "charged" liquids.

5 It will be understood that the structure described may be metal, porcelain, glass or other suitable material, or certain parts may be made of one material, and other parts 10 from a different material, depending on costs of material, conditions of operation, etc.

15 It will be understood further, that changes in details may be made in the constructions described without departing from the spirit or substance of the invention the scope of the invention being as broad as is commensurate with the appended claim.

20 The structure embodied in Figs. 1 to 5 permits of the invention being employed on bottles having bottle necks as ordinarily constructed, whereas, in Fig. 6, the valve seat is shown as forming an integral part of the bottle.

25 Having thus fully described the inven-

tion, what I claim as new, and desire to secure by Letters Patent, is:

A non-refillable bottle embodying a neck provided on its exterior with an annular groove and on its interior with an inverted frusto conical seat, an inverted hollow conical valve associated with the seat and having formed therewith integral guiding arms projecting upwardly in alignment with the tapered face of the valve of which face the 30 arms are a continuation, a cap positioned to house the valve and cover the mouth of the bottle, the lower end of which cap engages the groove in the neck of the bottle to support the cap in position and the top of which 35 cap is provided with a discharge opening, and a baffle plate positioned within the cap, above the valve, and spaced from the discharge opening by arms formed integral with the baffle plate and secured to the top 40 of the cap around the discharge opening.

45 In testimony whereof I have signed my name to this specification.

PHILIP ALÒ.
